Primary Examiner — Susan Moon Lee

(57) **CLAIM**

The ornamental design for a water drinking device for pets, as shown and described.

DESCRIPTION

FIG. 1 is a front elevational view of a water drinking device for pets showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, rear and left side perspective view thereof; and,

FIG. 9 is a bottom, front and left side perspective view thereof.

(Continued)

The broken lines in the drawings illustrate portions of the water drinking device for pets which form no part of the claimed design.
